UNITED STATES PATENT OFFICE

140,503

DESIGN FOR A COMBINATION COLLAPSIBLE BABY'S AUTOMOBILE AND SWING SEAT

Sebastian J. Geluso, Brooklyn, N. Y., assignor of
one-half to Henry M. Lawn, Brooklyn, N. Y.

Application June 26, 1944, Serial No. 114,192

Term of patent 7 years

(Cl. D15—8)

To all whom it may concern:

Be it known that I, Sebastian J. Geluso, a citizen of the United States of America, residing in Brooklyn, in the county of Kings and State of New York, have invented a new, original, and ornamental Design for a Combination Collapsible Baby's Automobile and Swing Seat, of which the following is a specification, reference being made to the accompanying drawing, forming a part thereof, in which

Figure 1 is a front elevational view of a combination collapsible baby's automobile and swing seat showing my new design.

Figure 2 is a side elevational view of Figure 1.

Figure 3 is a front perspective view thereof.

Figure 4 is a perspective view thereof as the device appears in the collapsed position.

Figure 5 is a front perspective view on a somewhat reduced scale and showing the device as it appears when used as a swing, the dot-and-dash lines being illustrative only.

The dominant features of my new design are shown in full lines in the drawing.

I claim:

The ornamental design for a combination collapsible baby's automobile and swing seat, as shown and described.

SEBASTIAN J. GELUSO.
